(57) **CLAIM**

We claim the ornamental design for an oven range, as shown and described.

DESCRIPTION

FIG. 1 is a perspective view of an oven range showing our new design:

FIG. 2 is a front elevation view thereof;

FIG. 3 is a rear elevation view thereof;

FIG. 4 is a left-side elevation view thereof;

FIG. 5 is a right-side elevation view thereof;

FIG. 6 is a top plan view thereof; and,

FIG. 7 is a bottom plan view thereof.

The broken lines in the drawing figures are included for the purpose of illustrating environment and form no part of the claimed design.
